THOMAS F. CROCKER, OF CHICAGO, ILLINOIS, ASSIGNOR TO RESERVE HOLDING COMPANY, OF KANSAS CITY, MISSOURI, A CORPORATION OF DELAWARE

TELEPHONE SYSTEM

Application filed January 28, 1929. Serial No. 335,443.

This invention relates to telephone systems in general but is more particularly concerned with small private installations of the type commonly used in commercial establishments and in various branches of municipal administration such as fire and police departments. The invention is concerned primarily with apparatus for rendering special services in systems of the above type.

By way of example, the application of the invention to a police department automatic telephone system will be described. Automatic exchanges installed for this service are commonly of the type known as private automatic exchanges, abbreviated as P. A. X., and may vary in size from a few lines to several hundred lines. In referring to the automatic exchange, the abbreviation P. A. X. will be used throughout the specification.

In addition to the automatic exchange, a telephone system of the above type usually includes a special service desk or operator's position. This desk may be in charge of an operator or a desk sergeant and is usually located in the department headquarters. The main purpose of this special service desk is to provide a central point to which the various patrol officers may report and from which they may obtain information pertinent to the discharge of their duties. Special means may also be provided so that a selected group of lines such as those extending to the various branch police stations may be called as a group for conference purposes or so that an important message can be transmitted simultaneously to all stations concerned.

The object of the invention is the provision of new and improved circuits for systems of the above type with particular reference to the operator's telephone circuit and associated trunk circuits. It is to be understood, however, that the application of the invention is not limited to a police department P. A. X. and that the invention is described in conjunction therewith merely for the purpose of illustrating one method of utilizing the features of the invention. Other applications will be readily apparent.

According to one feature of the invention, a two-way trunk extending between the P.

A. X. and the operator's position terminates in a relay group at the special service desk. A battery feed bridge in the relay group normally supplies battery to the operator's telephone set. On outgoing calls over the trunk, 55 the battery feed bridge is disconnected and a loop control circuit from the operator's set is extended to the regular switch train in the P. A. X.

According to another feature of the invention, a single key is used to extend outgoing calls and to answer incoming calls over the two-way trunk. As long as the key is in answering position a busy potential is maintained on the guarding conductor to prevent 60 another call from coming in while the operator's set is connected up. The release of the switch train in the P. A. X. is not interfered with.

Another feature is the arrangement whereby important messages may be quickly transmitted to a selected group of stations. These stations can be connected to the group calling apparatus regardless of their busy or idle condition. Each station of the group is provided with a separate battery feeding bridge when connected to the common talking circuit which improves transmission and affects the operation in other ways which will be explained in detail later on. 70

Another feature is the arrangement whereby an incoming call may be telephonically connected to the group call circuit to permit the party making the call to transmit an important message to the group stations or to 75 "listen in" while the message is being transmitted by the operator. Other calls in progress can be disconnected from the operator's set to prevent other than the group stations from hearing the message. 80

The foregoing features, together with others not specifically mentioned, will be described fully hereinafter.

The accompanying drawings comprising 85 Figs. 1 and 2 show by means of the usual circuit diagrams a sufficient amount of equipment in a telephone system embodying the features of the invention to enable the invention to be understood. The drawings should be arranged with Fig. 2 directly beneath Fig. 100

1, so that the four vertical lines extending to the lower and upper margins, respectively, of the two figures will be in alignment.

Referring now to Fig. 1, the operator's telephone set OT is of the well-known cradle type with an anti-side tone circuit, comprising the usual talking and impulsing instrumentalities. A telephone set of this type is shown in United States Patent No. 1,689,598 to H. C. Pye. The bells shown in the drawing are ordinarily provided with telephone sets but have no function in the present instance other than to balance the transmitter and receiver circuits.

15 A two-way trunk comprising three conductors extends from the trunk relay group TRG to a line switch LS in the P. A. X. The trunk is also accessible in the banks of the connectors of the P. A. X. The key K¹, located at the operator's position, is used for extending or answering calls over the trunk. The trunk relay group is interconnected with the group call equipment in such a manner that the initiation of a group call will release an outgoing call, as will be described in detail later on.

Referring to Fig. 2, the common group relay equipment CGR is connected to the operator's telephone set by means of the key K². 30 Associated with the common relay group are a number of individual relay groups of which one relay group, IGR, is shown. The other individual relay groups are similar in every respect to IGR and are connected in multiple to the common equipment as shown. Each telephone line from a group station such as T terminates in a relay group such as IGR from which connections extend to a line switch LS¹ in the P. A. X. Calls over these lines normally proceed as ordinary calls over the regular P. A. X. switch train. It will be noted that a signal lamp L² is provided for each individual relay group.

45 Relay group IR terminates a selector level trunk. Calls coming in over this trunk operate the signal lamp L³ and the calling party is given a ring back tone. A battery feeding bridge connected to the trunk supplies transmission battery to the calling party. In case it is desired to hold a connection temporarily while making other calls, the key K³ is operated to the left. If the calling party releases before the key is restored to normal position, a busying potential is placed on the guard conductor to prevent another call from coming in over the trunk.

Having briefly described the various pieces of apparatus and the general functions thereof, a detailed description will now be given.

50 When the operator's telephone set is not in use the transmitter-receiver member will be resting in the cradle normally provided and plunger 5 will be depressed, opening the contacts 6 and 7. The talking conductors will, therefore, be open at the above contacts

and no battery will flow in the circuit of the transmitter and receiver. When the transmitter-receiver member is lifted from the cradle, the plunger 5 is actuated by a spring (not shown) permitting the contacts 6 and 7 to close the talking conductors through to the transmitter and receiver.

70 In order to make a call over the outgoing trunk, key K¹ is operated to the right. A circuit is closed from battery, contact 134, conductor 132, winding of relay 103, armature 114 and its resting contact, and resting contact and armature 116 to ground. Relay 103 operates over the above-traced circuit and at armature 117 and its working contact 80 connects the speaking conductor 2 through to the line switch LS by way of armature 124 and its resting contact and conductor 128'. At armature 119 and its working contact 85 talking conductor 3 is connected through to line switch LS by way of normally closed contacts controlled by armature 127 and conductor 129. The line switch is operated in the usual way over a loop including an operator's transmitter, receiver, calling device, and a contact controlled by plunger 5. The line switch operates in the well-known manner and by way of wipers 136, 137, and 138 extends the connection to an idle trunk such as that comprising conductors 138', 139, and 95 140. This trunk leads to a local selector in the P. A. X. The operator may now proceed to set up the connection by operating the calling device CD. When the calling device is turned off-normal the transmitter and receiver are shunted out in the usual way to improve the impulsing circuit. As the calling device returns to normal the interrupter springs are opened in the usual way and interrupt the loop to operate the selector and 100 other switches in the P. A. X. 105

110 The operator may release the connection by restoring the connection key K¹ to normal, thus opening the circuit of relay 103 which deenergizes and opens the loop circuit to the line switch at armatures 117 and 119. The battery feeding bridge 104 is again connected across the talking conductors 2 and 3 at normally-closed contacts controlled by armatures 117 and 119. In the foregoing connection it is assumed that the group call equipment is not in use and relay 101 was not energized. The operation of this relay will be described in detail at a point further along in the specification.

115 Assume now that a call is extended to the trunk by way of a connector in the P. A. X. The operation of connector and line switch under these circumstances is well known in the art and will not be described in detail. 120 If the trunk is idle the test wiper of the connector finds battery potential on the test contact and switches through in the usual manner. The cut-off relay of the line switch also operates and disconnects the normal bat- 125 130

tery and ground connections from the line. Ringing current is then sent out by the connector over its negative wiper and bank contacts, conductor 128', armature 121 and its resting contact, condenser 112, winding of relay 107, conductor 129, bank contact and wiper of the connector to ground. Relay 107 operates in response to the ringing current impulses from the connector and at armature 128 and its working contact closes an obvious circuit for relay 106. Relay 106 operates and at armature 126 and its working contact closes a locking circuit for itself including armature 122 and its resting contact. At armature 124 a point in the talking circuit is opened to prevent any possibility of ringing current being connected to the operator's set when the call is answered. At armatures 125 and 127 a part of the ring-cut-off circuit is closed. Relay 107 continues to operate each time an impulse of ringing current is transmitted by the connector but has no further function in this connection. The initial operation of relay 107 and the subsequent locking of relay 106 places a ground on conductor 131 which lights the signal lamp L^1 , thus notifying the operator that a call has come in over the trunk.

To answer the call key K^1 is operated to the left, thereby closing a circuit from ground, contact 135, conductor 133, winding of relay 102, winding of relay 105, to battery. Relays 102 and 105 operate over the above-traced circuit. Relay 102, on operating, at armature 116 and its working contact connects ground to release trunk conductor 130, the purpose of which will be described later on. Relay 105, on operating, at armature 120 and its working contact closes a point in the talking circuit, at armature 121 the circuit of relay 107 is opened at the resting contact, and the ring-trip circuit is closed at the working contact. The ring-cut-off relay of the connector operates over the previously traced ringing circuit except that armature 121 being operated resistance 110, armature 125, armature 122, and ground are now connected up and the relay operates over this direct current circuit. At armature 122 the locking circuit of relay 106 is opened, and the relay deenergizes. The removal of ground from the locking circuit of relay 106 also extinguishes the lamp L^1 . At armature 123 and its working contact the talking circuit is closed through to conductor 3. Shortly after relay 105 operates relay 106, which is slow-acting, deenergizes and at contacts controlled by armature 127 completes the talking circuit which may be traced by way of conductor 129, contacts controlled by armature 127, armature 123 and its working contact, condenser 109, conductor 3, to the operator's telephone circuit, conductor 2, condenser 108, armature 120 and its working contact, conductor 128', and thence through the regular

talking circuit of the connector. The battery feeding impedance 104 is now bridged across the talking conductors at contacts controlled by armatures 117 and 119, feeding talking battery to the operator's telephone set. In case the calling subscriber hangs up, the switches in the automatic exchange will release in the regular way. If the operator does not restore the key K^1 immediately the ground on the release trunk conductor by way of armature 116 and its working contact will prevent another call from coming in on the trunk at this time. When the operator finally restores key K^1 to normal the circuit for relays 102 and 105 is opened and these relays return to normal. As in the previous connection it is assumed that the group calling circuit was not in use and that relay 101 was not energized. In case the operator restores key K^1 to normal before the calling party disconnects, the relays in the trunk relay group TRG will restore to normal and disconnect the trunk from the operator's telephone set. The switches in the P. A. X. are not released until the calling party hangs up.

Assuming now that some important information is to be transmitted to a selected group of stations such as station T. Key K^2 is operated, closing the following circuit: ground by way of resting contact and armature 115, resistance 113, conductor 142, contact 214, armature 216 and its resting contact, winding of slow-acting relay 202 to battery. Relay 202 operates and at armature 217 and its working contact closes an obvious circuit for relay 203. Relay 203 operates and at armature 218 closes a circuit for the upper winding of relay 201. Relay 201 operates and at armature 215 and its working contact closes a locking circuit for its lower winding including operated contacts 213, conductor 141, winding of relay 101 to ground. Relay 101 operates and disconnects ground from the starting lead 142, and at armature 114 opens the calling circuit of the outgoing trunk relay group TRG. Relay 201 also opens the circuit of relay 202, which, however, does not release immediately due to its slow release characteristics. Relay 203, in the meantime, has at armature 219 and its working contact closed a circuit from ground to normally closed contacts controlled by armature 229, winding of relay 207 and other corresponding relays to battery. Shortly after relay 202 deenergizes, relay 203 also deenergizes and removes the ground from the upper winding of relay 201 and also from the energizing circuit of relay 207. Relay 201, however, remains locked up in series with relay 101. Relay 207, on operating, closes a locking circuit for itself including armature 229 and its working contact, armature 223 and its resting contact, and operated contacts 210 to ground. At armatures 227 and 231 and their respective working contacts, the conductors 238 and 239

of the line extending to the station T are connected to the ringing circuit which may be traced from battery, by way of ringing current generator G, winding of relay 206, armature 222 and its resting contact, armature 227 and its working contact, conductor 238, telephone instrument at station T, conductor 239, armature 231 and its working contact, armature 225 and its resting contact to ground. The other lines in the group corresponding to that extending to station T are also connected up to the ringing circuits of the various individual relay groups, such as IGR, which are connected in multiple to the common relay group CGR as shown. Assuming that station T was not busy in another connection at this time, the bells at that station will be rung continuously over the ringing circuit previously traced. When the receiver is lifted at the called station a direct current path is closed over which relay 206 operates. In case station T had been busy in another connection when the group call was made, the operations previously described would be the same except that the receiver being off at the called station, relay 206 would operate immediately over the called station loop. On operating, relay 206 closes a circuit for relay 205 at armature 226 and its working contact. Relay 205 operates and at armature 224 and its working contact closes a locking circuit for itself including armature 230 and its working contact. The talking conductors of the called line are disconnected from the ringing circuit at armatures 222 and 225 and their resting contacts and at their respective working contacts are connected up to the two windings of battery feed relay 204. At armature 223 and its resting contact the locking circuit of relay 207 is opened; relay 207, however, is slow acting and does not release immediately. Relay 204 operates over the previously traced called line loop and at armature 220 and its working contact closes another locking circuit for relay 207. At armature 221 and its resting contact the circuit of lamp L^2 is opened and the lamp is consequently extinguished. Similar operations take place in each of the other relay groups as the various called stations answer. When all lamps, such as L^2 , have been extinguished the operator is informed that all stations have answered and may proceed to transmit the message.

Talking battery for the operator's set is fed through the impedance 104 of trunk relay group TRG. It will be noted that relay 101 operated in series with relay 201 when the group call was extended. Relay 101 at armature 114 opens a circuit of relay 103 which is without effect if no call is in progress on the outgoing trunk. However, if an outgoing call has been in progress over this trunk, the release of the relay 103 opens the circuit to the equipment in the automatic ex-

change and also connects battery feed relay 104 to the operator's telephone set. Incoming calls over the two-way trunk would not be affected and consequently a calling station would be connected up with the group call equipment, thus permitting a party on this line to transmit a message to the station of the selected group. Incoming calls, however, may be disconnected from the group equipment by restoring key K^1 to normal. It is apparent that as long as the group call equipment is in use the operator is prevented from making an outgoing call over the two-way trunk but is not prevented from answering calls over this trunk.

Returning now to the group calling equipment, it will be noted that relay 207, on operating, at armature 228 and its working contact connected a ground to release trunk conductor 234 which serves to mark the line busy to connectors in the automatic exchange. In case a call had been in progress from the station T when the group call is made, this ground would serve to maintain the automatic switches in operated position during such time as station T is connected to the group call equipment.

Assuming now that the party at station T wishes to be disconnected from the group equipment without waiting for the operator to release the group connection. By actuating the switch hook the circuit of relay 204 is opened and that relay releases, thereby opening the locking circuit of relay 207 at armature 220. Relay 207 deenergizes and connects the talking conductors of the station T back to the trunk conductors leading to line switch LS¹. At armature 228 ground is removed from release trunk conductor 234, thereby releasing the switches in the P. A. X. and also removing the busy potential from the test contacts of the connector banks. The locking circuit of relay 205 is opened at armature 230 and that relay restores, thereby connecting up the normal ringing circuit, which, however, is now opened at armatures 227 and 231 and their respective working contacts. Other stations of the connector group are not affected in any way and the lamp L^2 does not light again.

When key K^2 is restored to normal, the initial locking circuit for relays such as 207 is opened at contact 210 and the operator's telephone set is disconnected from the group circuit at contacts 211 and 212. The locking circuit for relays 201 and 101 is opened at contact 213 and these relays restore. Relay 101 again connects ground to the starting conductor of the group call equipment at armature 115 and its working contact, and also closes a point in the circuit of relay 103, again making the trunk available for outgoing calls. Relay 201, on restoring, opens a point in its locking circuit at armature 215 and at armature 216 and its working contact

70

120

125

130

5 closes the normal energizing circuit for relay 202. The individual relay group equipment, however, is still under the control of the called station and when the various stations disconnect, this equipment releases as previously described.

10 Information calls are extended to the operator by way of selector level trunks terminating in relay groups such as IR. Assuming that a selector in the P. A. X has advanced its wipers 279-281 into engagement with contacts 276-278, terminating conductors 266-268, relay 252 will operate over the calling line loop. At armature 260 and 15 its working contact an obvious circuit is closed for relay 253, and at armature 261 and its working contact the ring-back tone equipment is connected to the calling line by way of condenser 282 and armature 258 and its resting contact. Relay 253 operates 20 and at armature 262 and its working contact connects ground to the release trunk to maintain the switches in the automatic exchange in operated position; at armature 253 and its working contact an obvious circuit is closed for relay 254; at armature 264 and its working contact a circuit is closed for lamp L³ including armature 259 and its resting contact and conductor 274. Lamp 25 L³ lights, to indicate to the operator that a call has come in over the information trunk. The calling party is informed that the call has been extended by means of the ring-back tone.

30 To answer the call key K³ is operated to the right, thereby connecting the operator's telephone set to the talking conductors of relay group IR at contacts 271 and 272. At contact 273 a circuit is closed for the lower winding of relay 251 which operates and at armature 259 and its working contact closes a locking circuit for its upper winding including armature 264 and its working contact. At armature 258 the ring-back tone 35 is disconnected from the line and at armature 257 a ground is placed on a branch of the release trunk conductor 268 which, however, is open at armature 265 and its resting contact. The operation of relay 251 also 40 opens the circuit of lamp L³ at armature 259 and its resting contact, thereby extinguishing the lamp. The call may now proceed, talking battery for the calling line being fed through relay 252 and talking battery for the operator's telephone circuit being fed through impedance 104 of relay group TRG.

45 Should the operator desire to hold up the connection while making another call, key K³ is operated to the left, thereby disconnecting the operator's set from the talking leads of the trunk and closing another locking circuit for relay 251 including contact 270. The circuit for hold lamp L⁴ is closed at contact 269, this lamp lighting to indicate 50 to the operator that the call is being held.

When the receiver is replaced at the calling station the circuit of relay 252 is opened and that relay restores followed by the restoration of relays 253 and 254, both of which retain their armatures in operated position a short time after relay 252 restores, due to their slow releasing characteristics. Relay 253 on restoring removes ground from release trunk conductor 268, thus permitting the switches in the P. A. X to release in the regular manner. Relay 254 remains operated a short time after relay 253 restores and maintains the release trunk conductor opened at armature 265. When these relays are restored to normal, ground from armature 257 and its working contact is placed on release trunk conductor 268 by way of armature 265 and its resting contact to mark the trunk busy to incoming calls. This ground is maintained on the guarding conductor 85 when key K³ is operated in order to prevent a call from coming in when the equipment is not in condition to give the proper signal to the operator or the ring-back signal to the calling station.

90 It will be noted that as long as key K³ is operated to the right the incoming call is connected to the operator's set and may hear conversation on either the group call equipment or on the two-way trunk. To disconnect the information trunk from the talking circuit it is only necessary to restore key K³ to normal or to holding position. When K³ is restored to normal position the energizing circuit of relay 251 is opened and if the calling party has previously disconnected this relay deenergizes. If the calling party is still on the line, relay 251 remains operated over its upper winding. Signal lamp L³ does not light at this time since its 95 circuit is open at armature 259.

100 Having described this invention, what is considered new and is desired to have protected by Letters Patent will be pointed out in the appended claims.

110 What is claimed is:

1. In a telephone system, an operator's telephone, a first trunk and a second trunk, means for extending a connection from said telephone over either of said trunks, a battery feeding bridge normally connected to said telephone, means responsive to the extension of a connection over said first trunk for disconnecting said bridge, and means responsive to the extension of a connection over 115 said second trunk for releasing said first connection and for re-connecting said bridge.

2. In a telephone system, an operator's position, an automatic exchange, a trunk extending from the operator's position to the exchange, said trunk comprising two normally disconnected sections, means for extending a connection from the operator's position to the exchange or from the exchange to the operator's position via said trunk, a relay 125

70

75

80

85

90

95

100

105

110

115

120

125

130

bridged across the first section of said trunk, a second relay bridged across the second section of said trunk, means responsive to the extension of a connection from the operator's position for disconnecting both of said relays from the trunk and for directly connecting the two sections of said trunk, and means responsive to the extension of a connection from the exchange for disconnecting only said second relay and for connecting the two sections of said trunk through condensers.

3. In a telephone system, an operator's position, a plurality of stations, a plurality of signals at said position each of said signals corresponding to a particular one of said stations, a common talking circuit, means for extending a connection from said position to said talking circuit, means responsive to said connection for simultaneously signaling said stations, and means responsive when a station answers for connecting the station to said common talking circuit and for actuating the corresponding signal.

4. In a telephone system, an operator's position, a plurality of stations, a common talking circuit, means for extending a talking connection from said position to said talking circuit, means responsive to the extension of the connection for simultaneously signaling said stations, means responsive when a station answers for connecting the station to the common talking circuit, and battery feeding bridges individually connected to each station during the connection.

5. In a group calling circuit, a common talking circuit, a plurality of lines, means for simultaneously signaling said lines, means for connecting said lines to said talking circuit, and means for connecting battery to each line through a separate feeding bridge responsive to the connection of the line to the common talking circuit.

6. In a telephone system, an operator's position, an incoming trunk, a plurality of stations having individual lines any of which may be idle or busy in other connections, a group calling circuit, means controlled by the operator for establishing a connection with said stations simultaneously via said group calling circuit regardless of the busy or idle condition of said stations, and means controlled by the operator for establishing a talking connection between said incoming trunk and said group connection.

7. In a telephone system, an operator's telephone set, a two-way trunk line, means for connecting said set to the trunk line to extend an outgoing call or to answer an incoming call, a source of current normally connected across the talking conductors of the set for supplying talking current or incoming calls, and means for disconnecting said current source on outgoing calls.

8. In a telephone system, an operator's telephone set, a plurality of trunk lines

adapted to be associated with said set, a source of talking current normally connected with said set, and means for disconnecting said current source from the set responsive to a particular one of said trunks being associated therewith.

9. In a telephone system, a two-way trunk line comprising two normally disconnected sections, a source of current normally bridged across the talking conductors of the first section, means responsive to the answering of an incoming call over the trunk line for connecting the talking conductors of the two sections through condensers, and means responsive to the extension of an outgoing call over the trunk line for directly connecting the talking conductors of the two sections and for disconnecting said current source.

10. In a telephone system, an operator's position, a plurality of stations, a line for each station, a common talking circuit, means for extending a talking connection from said position to said talking circuit, means responsive to the extension of the connection for simultaneously signalling said stations via the associated lines, means responsive when a station answers for connecting the associated line to the common talking circuit, and battery feeding bridges individually connected to each line during the connection.

In witness whereof, I hereunto subscribe my name this 25th day of January, A. D. 1929.

THOMAS F. CROCKER.
